UNITED STATES PATENT OFFICE.

CLIFFORD G. MILLER, OF NEW YORK, N. Y., ASSIGNOR TO THE UNDERSELLER COMPANY, INC., OF NEW YORK, N. Y., A CORPORATION OF NEW YORK.

DISPLAY APPARATUS.

1,150,053.

Specification of Letters Patent. Patented Aug. 17, 1915.

Application filed September 13, 1913. Serial No. 789,607.

To all whom it may concern:

Be it known that I, CLIFFORD G. MILLER, a citizen of the United States, residing at New York, in the county of New York and State of New York, have invented certain new and useful Improvements in Display Apparatus; and I do hereby declare the following to be a full, clear, and exact description of the invention, such as will enable others skilled in the art to which it appertains to make and use the same.

This invention relates to improvements in display apparatus, and has as its essential object the production of a novelty designed and adapted especially for attracting the attention and arousing the curiosity of prospective purchasers.

With this and other detail objects in view, as will in part be hereinafter pointed out and in part become apparent, the invention comprises certain novel constructions, combinations and arrangements of parts as subsequently specified and claimed.

In the accompanying drawing: Figure 1 is a view in front elevation of an apparatus embodying the features of the present invention. Fig. 2 is a longitudinal vertical section therethrough taken on the plane indicated by line 2—2 of Figs. 1 and 3. Fig. 3 is a view similar to Fig. 1 taken from the reverse side. Fig. 4 is an enlarged, detail fragmentary section taken approximately on the plane indicated by line 4—4 of Fig. 3.

Referring to the drawing by numerals, 1 indicates a glass plate, such for instance, as the plate-glass show-window of a store or shop, and to the outside surface of said plate is cemented or otherwise appropriately fixed an annular housing 2 whose interior is formed into a circular space in which is disposed a disk 3 formed of soft iron or other magnetic substance, the said disk being free to be shifted within the housing toward and away from the plate 1. To insure maintenance of the disk 3 spaced to the farthest extent permitted by the housing from the plate 1, a spring 4 is interposed between the plate and the disk 3. An appropriate button 5 engages the disk 3 and extends through an aperture in the housing 2 for enabling an operator to press disk 3 toward plate 1 against the tension of spring 4. As a convenient means of manufacture, the button 5 is preferably stamped

from the material of disk 3, the button being therefore hollow, and the spring 4 having its outer end seated within the hollow portion of the button. Thus the spring may be compressed to an extent enabling the disk 60 3 to move into contact with the outer face of plate 1.

Arranged at the inside of the plate 1, is a case 6, suspended upon a cable 7, or otherwise appropriately supported with the front 65 of the case 6 contacting with the inner face of plate 1, the case 6 being opened toward the plate. A cross piece 8 is fixed within the casing 6 and sustained by said cross piece 8 is an electrical motor 9 of any ordinary and conventional type, the armature of which has its shaft 10 extending beyond the regular bearings of the motor, the outer end portion of the shaft end extending centrally through a disk 11, the disk being appropriately locked onto the shaft by nuts or other convenient attaching means. The inner face of the plate, is preferably painted or coated with opaque material throughout that portion corresponding to the outline of the outermost parts of the case 6, and the presence of this opaque substance is indicated in Fig. 1 by the showing in dotted lines of parts which would otherwise appear in full lines. By preference, however, 75 segments or other appropriate portions of the plate 1 immediately in front of the disk 11 are left transparent as indicated at 12—12 and 13—13. The disk 11 may be of any substance, but is preferably opaque, and is 80 provided on its front face with colored insignia, such as a star 14, or other design adapted to attract attention of one standing on the outside of the window, when the star or other design is partly exposed through 85 the transparent portions 12 and 13, the appearance being rendered especially attractive when the disk 11 is revolved by the operation of the motor 9.

One binding post of motor 9 is connected 100 by a conductor 16 to a binding post 17 carried by one side of the case 6, a conductor 18 leading from the binding post 17 to a battery or other source of supply 19, and a conductor 20 leads from the battery 19 to 105 a binding post 21 similar to the post 17, and a conductor 22 leads from the post 21 to a contact 23 of a switch 24, a conductor 25 leading from the switch 24 to that binding post of motor 9 opposite the binding post 110

with which conductor 16 connects. Thus, when switch 24, which is of the spring type, is pressed laterally sufficiently to touch the contact 23, the circuit is closed through the 5 several parts just described for supplying current to motor 9, and thereupon, the disk 11 is caused to revolve.

The switch 24 and contact 23 are supported by and insulated from a cross bar 26 10 fixed to the outer edges of the sides of case 6, and a similar cross bar 27 is similarly arranged above the bar 26. Fixed to and projecting inwardly from the inner face of bar 27 are brackets 28-28 from which is 15 suspended an arm 29, the said arm having laterally extending fingers 30 at its upper end projecting across and resting upon the brackets 28, each finger 30 being preferably provided with a knife edge for enabling the 20 arm 29 to remain vertical when free, and to readily swing laterally upon said knife edges as pivots when subjected to lateral pressure. A horse-shoe magnet 31 is disposed for having its arms inclose the greater 25 portion of the arm 29, and plates 32 and 33 are bolted together as indicated at 33'-33', the bolts 33' passing through the material of the arm 29, of course, effectively fixing plates 32 to said arm, and the outer end portions of the plates extend on relative opposite sides of the respective arms of the horse-shoe magnet 31, and are firmly clamped thereagainst when the bolts 33' are threaded home. Thus the horse-shoe magnet 31 is 30 free to swing therewith, it being the intent and purpose to have the plates 32 engage the arms of the magnet 31 at those points which represent the transverse line of balance of the magnet, so that that portion of the magnet 31 above the plates 32 weighs approximately the same as those portions of the arms of the said magnet below said plates. Hence, there is no natural tendency to overbalance in either direction, and the magnet 45 is effectively suspended and pivotally supported to swing freely, the main portion of arm 29 being disposed centrally in the width and thickness of the magnet as indicated clearly in Fig. 2, for preventing any overbalance in the direction of the thickness of the magnet 31.

Merely as a matter of facility of construction and operation, the lower extremity of arm 29 is extended below the magnet as indicated at 34, extending down past the spring switch 24 in position for pressing the same outwardly into contact with contact point 23, when the arm has its lower portion swung outwardly. It is to be observed, that 55 the lower extremities of the arms of the magnet 31 are approximately in the horizontal planes of disk 3, and the disk is so disposed as to be sufficiently beyond the field of the magnet, when the disk is in its outermost position, to allow the magnet to remain

vertical, and when the disk is pressed inwardly, it enters said field, and becoming magnetized, causes the lower portion of the magnet 31, in its effort to shorten the magnetic lines of force, to move outwardly, thereby moving the arm 29 and closing the contact between switch 24 and contact piece 23. 70

A lever 35 is pivoted to bar 26, and has its outer portions extending through a slot in one side of case 6, so as to provide an appropriate handle for manual manipulation. The inner portion of the lever 35, terminates in a soft iron piece or piece of other appropriate material adapted to serve as a keeper 36 for the magnet 31, the lever 35 being pivoted in position for causing the keeper to move up to a position extending across the poles of the magnet when the lever 35 is depressed from the outside of the case 6. When the said keeper 36 is disposed across 85 the poles of the magnet, the device is maintained positively out of operation, and the disk 3 is incapable of influencing the magnet, so that contact cannot be made between switch 24 and contact point 23 so long as the keeper 36 contacts with the poles of the magnet. 90

Segmental slides 37 are pivotally connected as at 38 to the back of the case 6, the axis of the pivot of these slides being connected 95 with the axis of revolution of disk 11. Said slides are provided with operating knobs or handles 39 adapted to be grasped manually for moving the slides pivotally toward and away from each other. The back of the case 100 6 is cut away at its lower portion for leaving an opening, indicated at 40, for enabling ready inspection of the lower portion of the rear face of the disk 11, and the slides 37 are employed to supplement the back to enable concealing variable portions of the disk. An arrow or other insignia, as indicated at 105 41, is painted or otherwise displayed on the rear face of the disk 11, and it is the object of the slides to render it more or less difficult to cause the arrow 41 to show when the disk 11 ceases revolving at any given time. For instance, if the slides 37 are moved upwardly to their widest open position, nearly 110 one-half of the rear face of the disk is exposed, and there will, therefore, be much more opportunity for the arrow to be exposed when the disk ceases to revolve than would be the case if the slides 37 were adjusted downwardly toward each other until 115 there was only sufficient space between them for the width of the arrow. The former condition might be considered that of the maximum chance, and the latter, that of the minimum. Obviously, an unlimited number of variations in the possible chances of maximum and minimum is made possible by variable adjustments, and relative adjustments of the slides 37. 120

It is believed that the operation of the in- 125

vention will be obvious from the foregoing, and it is apparent, of course, that the structure is adapted for numerous uses, such, for instance, as that of advertising a particular brand of goods, as, for example, the store-keeper might offer 25% reduction from the sale price of certain goods if a customer could make the arrow show. Such an apparatus in front of the shop-window would naturally interest passers-by, who only need to press the button 5, and thereupon the circuit for the motor 9, being closed by the action of the magnet 31, disk 11 would be revolved. Upon releasing the button, the operator would naturally be curious to know whether he had succeeded in making the arrow show, and to learn this fact, he would have to go into the store and look at the rear of the apparatus, which would have the effect of bringing him into the place of business and of giving him an opportunity to see the display of goods, which he probably would not have taken the time to note had his attention not been drawn by the advertising apparatus. Of course, the percentage of discount to be allowed as an inducement would naturally be varied according to the distances apart of the slides 37, since the chances of having to allow the discount would be proportionally varied. Obviously, the apparatus is adapted for many other uses, such as, for instance, a child's game apparatus with appropriate rules for governing the number of times the button could be pressed by any one operator with the greatest number of exposures of the arrow as the winning score.

What I claim is:—

1. In an apparatus of the class described, the combination, of a glass plate of a show window, of a movable advertising device on the inside of the plate, and means at the outside of the plate for controlling movements of the advertising device.
2. In an apparatus of the class described, the combination, with an imperforate plate, of a movable advertising device at one side of the plate, an electrical motor for actuating said advertising device, and means at the opposite side of the plate for effecting a closing of the circuit of the motor.
3. In an apparatus of the class described, the combination, with an imperforate plate, of a movable advertising device at one side of the plate, an electrical motor at the same side of the plate for actuating the advertising device, and means at the other side of the plate for controlling the making and breaking of the circuit of the motor.
4. In a display apparatus, the combination with an imperforate plate, shiftable display means at one side of the plate, a motor for actuating the display means, and means on the other side of the plate from the display means adapted to act through

the plate for controlling operations of the display means.

5. In display apparatus, the combination with a plate of glass, movable display means at one side of the glass plate, the glass plate 70 being imperforate, and means at the other side of the glass plate adapted to act through the plate for controlling movements of the display means through the glass plate.

6. In display apparatus, movable display 75 means, a switch for controlling movements thereof, a magnet for positioning the switch, and a disk of magnetic material spaced from and movable into and out of the field of the magnet for effecting switch actuating movements of the magnet. 80

7. In display apparatus, the combination with an imperforate, non-magnetic plate, a magnet at one side of the plate, and a disk 85 of magnetic material at the other side of the plate shiftably mounted and disposed to be shifted relative to the field of the magnet for actuating the magnet.

8. In a device of the class described, the combination, with an imperforate plate, of 90 a housing fixed thereto, an armature shiftable in the housing toward and away from the plate, a spring disposed between the plate and armature for pressing the armature away from the plate, and a magnet disposed at the opposite side of the plate in position for being influenced relative to movements of the armature. 95

9. In apparatus of the class described, the combination, with a transparent plate, of a 100 movable element visible from in front of the plate, said element being disposed in the rear of the plate, an indicator adapted to be positioned by the movable element and visible only at the rear of the plate, and means 105 at the front of the plate for effecting movement of the movable element.

10. In apparatus of the class described, the combination, with a support, of a movable element sustained thereby, and visible 110 at the front of the support, an indicator adapted to be positioned by the movable element, concealed from view at the front of the support and visible at the rear thereof, and means for moving the movable element. 115

11. In apparatus of the class described, the combination, with a support, a disk revolvably carried by the support, and visible from the front of the support, means disposed in front of the support for actuating 120 the disk, and an indicator carried by the disk, and visible only from the rear of the support.

12. In apparatus of the class described, the combination, with a support, of a disk 125 movably carried by the support, and visible at the front of the support, means for actuating the disk, means at the front of the support for controlling the actuation of the disk, and an indicator at the rear of the disk 130.

visible only at the rear of the support, and means for varying the range of visual display of the indicator.

13. In apparatus of the class described, 5 the combination, with a support, of a revolubly mounted disk carried thereby and visible at the front of the support and also visible at the rear of the support, the disk bearing an indicator at its rear face visible at 10 the rear of the support but invisible at the front of the support, means for revolving the disk, and means for concealing variable portions of the disk at the rear of the support.
14. In apparatus of the class described, 15 the combination, with a support, of a disk revolubly carried thereby and visible at the front of the support, an indicator on the rear face of the disk invisible from the front 20 of the support, means at the front of the support for actuating the disk, and a slide for concealing variable portions of the disk at the rear of the support.
15. In apparatus of the class described, 25 the combination, with a support, of a disk revolubly carried thereby, and visible at the front of the support, an indicator on the rear face of the disk invisible from the front of the support, means for actuating the disk, 30 means at the front of the support for controlling actuation of the disk, and a slide for concealing variable portions of the disk at the rear of the support, the slide being pivotally mounted to swing about an axis 35 alined with the axis of rotation of the disk.

16. In apparatus of the class described, the combination, with a support of a revolubly mounted disk, visible at the front and rear of the support, means for actuating the

disk, means at the front of the support for 40 controlling actuation of the disk, an indicator at the rear face of the disk visible from the rear of the support, but invisible from the front of the support, and a plurality of slides disposed in the rear of the disk 45 and adapted to be coöperatively slid to various positions in the rear of the disk for concealing variable portions of the disk from the rear.

17. In apparatus of the class described, 50 the combination, with a transparent plate, of a pivotally pendent arm, a horse-shoe magnet inclosing the arm and supported thereby, the magnet being disposed at one side of the plate, and an armature at the 55 other side of the plate adapted to be moved relatively to the field of the magnet for moving the magnet.

18. In apparatus of the class described, 60 the combination, with a support, and a transparent plate in front of the support, of an arm pivotally pendent from the support, a horse-shoe magnet extending longitudinally of and inclosing a portion of the arm, means clamping the magnet to the arm, the arm having a projection extending beyond the magnet, a switch in the path of the movement of said projection, and an armature at the opposite side of a transparent 65 plate from the magnet and disposed to be moved with respect to the field of the magnet for effecting movements of the magnet.

In testimony whereof I affix my signature in presence of two witnesses.

CLIFFORD G. MILLER.
